BATTERY TESTER

Benjamin F. W. Heyer, Greenwich, Conn.

Application March 29, 1955, Serial No. 35,272

Term of patent 14 years

(Cl. D26—5)

FIG. 2

Fig. 1 is a front perspective view of a battery tester showing my new design; and

Fig. 2 is a rear elevational view thereof.

I claim:

The ornamental design for a battery tester, as shown.
